COMB

Bronis Condron and James M. Condron, Pittsfield, Mass.

Application February 24, 1939, Serial No. 258,154

7 Claims. (Cl. 132—11)

Our invention relates to combs and more particularly to combs used in hairdressing.

In arranging the pin-curls on a finger-wave, it is necessary to use a comb very frequently. It is also necessary to hold the curls in proper position by means of hairpins. Heretofore, the hairdresser in making a curl, has been obliged to set aside the comb so that the fingers may be free to shape the curl and to insert hairpins. The comb of the present invention may be readily retained on the hand without being held by the fingers, thereby allowing the fingers to work freely and also making it unnecessary for the hairdresser to set aside the comb thereby greatly facilitating the process of finger-waving and also in many instances the process of permanent waving.

One of the objects of the present invention, is the provision of a comb which may be quickly and conveniently engaged by the hand of the person using the comb.

Another object of the present invention is the provision of a comb adapted to be positioned on the hand of the person using the comb in such a way as not to interfere with the free movement of the fingers.

Another object of the present invention is the provision of a comb which being held continuously on the hand is not so liable to come in contact with unsterilized surfaces.

Other objects of the present invention will be apparent to those skilled in the art on reference to the appended drawing in which:

Fig. 1 is a perspective view of our finger comb showing one embodiment thereof;

Fig. 2 is a plan view of the comb illustrated in Fig. 1;

Fig. 3 is a perspective view of a modified form of our invention;

Fig. 4 is a side elevation view of the comb illustrated in Fig. 3;

Fig. 5 is a sectional plan view of the comb of Fig. 4 taken in about the plane 5—5 thereof; and

Fig. 6 is an end elevation view of a further modification of our invention.

Similar numerals refer to similar parts throughout the several views.

The comb of our invention is preferably formed of hard rubber, but might be made of any suitable substance. Referring to the drawing and first to Figs. 1 and 2, the teeth of the comb, indicated by the numeral 1, project laterally from the base 2. Base 2, in the embodiment illustrated in Figs. 1 and 2, is provided with openings therein indicated by the numeral 3,

through which the index and second fingers, preferably, are inserted. The openings shown in Figs. 1 and 2 are two in number, but it will be understood that either a greater or lesser number of openings might be provided. In the embodiment shown in Figs. 1 and 2, the index and second fingers are inserted through the opening 3 and the thumb rests upon the projection 4, while the third finger rests on projection 5, both projections being curved so that the thumb and third finger will fit closely thereto. It will be understood that either one or the other or both of the projections 4 and 5 might be omitted.

Fig. 3 is a modified form of the invention in which a slot 6 is provided in the base 2 into which the fingers are inserted as shown in Fig. 4. It will be observed that the contour of the slot is such as to conform to the contour of the fingers, so that the comb may be held on the fingers without moving. Adjacent the closed end of the slot there is provided a projection 4 on which the thumb rests.

The base 2 of the comb is provided with a laterally extending projection 7 which preferably extends in the direction of the teeth of the comb and in spaced relation thereto and is adapted to be gripped by the fingers as shown in Fig. 4. The upper surface of the projection 7, on which the inner side of the fingers rest, is provided with shallow grooves 8 which assist in retaining the fingers in the slot. Furthermore, the free edge of projection 7 may be notched as shown at 9 to provide a firmer grip on the comb. The preferred configuration of the projection 7 is best illustrated in Fig. 5.

Referring to Fig. 6 there is illustrated a further modification of the invention in which the openings 10 in base 2 through which the fingers are inserted may be varied in extent. It will be observed that openings 10 are provided through which the index and second finger preferably are inserted. Distensible members 11 are secured to the base 2 in any preferred manner so that when the fingers are inserted through openings 10 the members 11 will be distended and the comb will be held firmly upon the fingers. Adjacent the opening through which the index finger is inserted there is provided projection 4 on which the thumb rests and which is curved slightly to enable the thumb to rest closely thereto. It will be understood that the members 11 may be made of material other than distensible material and that the extent of the openings 10 might be varied by other means.

What we claim is:

1. A comb of the character described comprising a base portion and teeth projecting laterally therefrom and substantially at right angles thereto, said base portion being provided with a projection extending substantially parallel to said teeth and adapted to be gripped by a finger extending through an opening in said base portion.
2. A comb of the character described comprising a base portion and teeth projecting from the upper part of said base and at an angle thereto, said base comprising spaced portions disposed beneath said teeth and adapted to engage two fingers of a hand when inserted therebetween; said portions being so constructed and arranged that the fingers inserted therebetween may extend through said base and generally in the direction in which said teeth project therefrom whereby to retain said comb on the hand with the teeth thereof overlying said fingers while the fingers may be freely flexed.
3. A comb of the character described comprising a base portion and teeth projecting from said base and at an angle thereto, said base having adjacent concave portions disposed below said teeth and adapted to receive and engage the upper sides of two fingers of the hand and means for engaging said fingers to hold them against said concave portions whereby the base of said comb may be stably retained on the fingers with the teeth thereof overlying said fingers while said fingers may be freely flexed.
4. A comb of the character described comprising an integral structure including a base portion having teeth projecting therefrom and at an angle thereto, said base having adjacent concave portions disposed beneath said teeth and adapted to receive and engage the upper sides of two fingers of the hand and portions below said concave portions adapted to engage the undersides of said fingers; and said portions be-

ing so constructed and relatively arranged as stably to support said comb on the fingers of a hand when said fingers are inserted therebetween while said fingers may be freely flexed.

5. A comb of the character described comprising a base portion and teeth projecting from said base and at an angle thereto, said base portion being provided with a pair of openings disposed below said teeth and adjacent each other and adapted to receive adjacent fingers of a hand; said openings being of such size as stably to support said comb on the fingers of a hand when said fingers are inserted therein while said fingers may be freely flexed.

6. A comb of the character described comprising a base portion and teeth projecting from said base and at an angle thereto, said base having adjacent concave portions disposed below said teeth and adapted to receive and engage the upper sides of two fingers of the hand, means for engaging said fingers to hold them against said concave portions whereby the base of said comb may be stably retained on the fingers with the teeth thereof overlying said fingers while said fingers may be freely flexed, and said base being provided with a projection adjacent the finger-engaging portions thereof.

7. A comb of the character described comprising a base portion and teeth projecting from the upper part of said base and at an angle thereto, said base comprising spaced portions disposed beneath said teeth and adapted to engage a first finger of a hand and a projection disposed to one side of said spaced portions and adapted to be engaged by a second finger of the hand; the finger-engaging portions of said base being so constructed and relatively arranged as to enable the comb to be retained on the fingers of a hand with the teeth thereof overlying the fingers.
